Inventor:

Henry F. Baker

UNITED STATES PATENT OFFICE.

HENRY F. BAKER, OF CENTREVILLE, INDIANA.

IMPROVEMENT IN MOLE-PLOWS.

Specification forming part of Letters Patent No. 25,618, dated October 4, 1859.

To all whom it may concern:

Be it known that I, HENRY F. BAKER, of Centreville, in the county of Wayne and State of Indiana, have invented a new and useful Improvement in Mole-Plows; and I do hereby declare that the following is a full, clear, and exact description of the same, reference being had to the accompanying drawings, forming part of this specification, in which—

Figure 1 is a side view of my invention. Fig. 2 is a plan or top view of the same. Fig. 3 is a transverse section of the same, taken in the line $x x$ of Fig. 1. Fig. 4 is a horizontal section of the same, taken in the line $y y$ of Fig. 1.

Similar letters of reference indicate corresponding parts in the several figures.

To enable those skilled in the art to make and use my invention, I will proceed to describe it.

A represents a draft-beam, which may be of any suitable length, and having at its front end adjustable gage-rollers B, the axis a of which is attached to bars $b b$, fitted one in each side of the beam, and connected at their upper ends by a cross-piece, c , through which a regulating-screw, d , passes into the top of the beam.

C is a knife, which has its front edge made sharp by a basil on each side. This knife has its upper end passing through a loop or guide, D, which is formed of a metal strap attached to the side of the beam A. The back, also, of the knife C is notched at equal distances apart, and a screw, E, which passes laterally into the beam A, serves as a stay to the knife, as the notches are fitted on said screw, either of them, according as the knife is adjusted higher or lower.

F is a wedge or key, which is driven between the front edge of the knife C and a shoulder, e , formed on the beam in consequence of a recess being made in it to receive the knife C. Therefore the knife, it will be seen, is retained in proper position by the screw E and the wedge F.

To the lower end of the knife C a conical shoe, G, is permanently attached. This share has a journal, g , projecting horizontally from

its back end, and a packer, H, is placed loosely thereon and secured on the journal by a pin, a^x . This packer H is formed of a frustum of a cone, the end which abuts against the back part of the share being the smallest in diameter. The packer is fluted or grooved spirally, as shown clearly in Figs. 1, 3, and 4.

To the back part of the draft-beam A two curved bars, $h h$, are attached. These bars project beyond the beam, and have a roller, I, fitted between them, said roller being in line with the knife C.

The operation is as follows: The team is attached to the beam A in precisely the same way as to an ordinary plow, and as the implement is drawn along the knife C and share G enter the earth to the depth of the share G, being regulated by adjusting the knife C and rollers B B. The knife C merely makes a narrow cut in the earth, which is closed by the pressure of the roller I; but the conical share G makes a cylindrical hole, which is increased in diameter by the packer H, said packer rotating in consequence of the resistance offered by the earth to its spirally-fluted periphery.

The packer not only increases the diameter of the opening or passage made by share G, but also compresses the earth tightly around it to prevent the casual filling of the same.

The whole device, it will be seen, is extremely simple, having no parts liable to become deranged by use, and it admits of being very strongly constructed, fully commensurate with the work to be performed.

Having thus described my invention, what I claim as new, and desire to secure by Letters Patent, is—

1. The arrangement and combination of the screw E, key F, knife C, share G, and revolving packer H, as and for the purpose herein shown and described.

2. The employment of a revolving mole or packer, H, substantially as and for the purposes herein shown and described.

H. F. BAKER.
